UNITED STATES PATENT OFFICE

GEORGE B. FRENCH, OF SOUTHAMPTON, NEW YORK, ASSIGNOR TO FRENCH ELECTRIC COMPANY, INC., A CORPORATION OF NEW YORK

DESIGN FOR A TELEPHONE-TRANSMITTER CASE

Application filed February 20, 1929. Serial No. 30,150. Term of patent 3½ years.

To all whom it may concern:

Be it known that I, GEORGE B. FRENCH, a citizen of the United States, and resident of Southampton, county of Suffolk, and State of New York, have invented a new, original, and ornamental Design for Telephone-Transmitter Case, of which the following is a specification, reference being had to the accompanying drawings, forming part thereof.

Fig. 1 is a front view and Fig. 2 is a side view, showing my new design for telephone transmitter case.

I claim:

The ornamental design for a telephone transmitter case as shown.

GEORGE B. FRENCH.
